UNITED STATES PATENT OFFICE

109,252

DESIGN FOR A COMBINED INDICATING AND CONTROL DEVICE FOR RADIO RECEIV- ERS

Donald H. Mitchell, Chicago, Ill., assignor to Gal-
vin Manufacturing Corporation, Chicago, Ill.,
a corporation of Illinois

Application January 31, 1938, Serial No. 74,731

Term of patent 7 years

To all whom it may concern:

Be it known that I, Donald H. Mitchell, a citizen of the United States, residing at Chicago, in the county of Cook and State of Illinois, have invented a new, original, and ornamental Design for a Combined Indicating and Control Device for Radio Receivers, of which the following is a specification, reference being had to the accompanying drawing, forming part thereof, in which:

Figure 1 is a plan view of my design for a combined indicating and control device for radio receivers,

Figure 2 is a front elevation thereof, and
Figure 3 is an end view thereof.

I claim:

The ornamental design for a combined indicating and control device for radio receivers as shown.

DONALD H. MITCHELL.
